UNITED STATES PATENT OFFICE

104,286

DESIGN FOR A CASKET HANDLE OR SIMILAR ARTICLE

Luther E. Ohls, Galesburg, Ill.

Application October 8, 1936, Serial No. 65,207

Term of patent 7 years

To whom it may concern:

Be it known that I, Luther E. Ohls, a citizen of the United States and a resident of the city of Galesburg, county of Knox, and State of Illinois, have invented a new, original, and ornamental Design for a Casket Handle or Similar Article, of which the following is the specification, and reference being had to the accompanying drawing, forming a part thereof.

Fig. 1 is a front view of a casket handle or similar article showing my new design.

Fig. 2 is an end view of the design shown in Fig. 1.

Fig. 3 is a detail perspective view of one of the lugs shown in Fig. 1.

I claim:

The ornamental design for a casket handle or similar article as shown.

LUTHER E. OHLS.
